UNITED STATES PATENT OFFICE.

ROBERT WALTER, OF ST. LOUIS, MISSOURI.

DESIGN FOR A BASKET.

59,696.

Specification for Design.

Patented Nov. 15, 1921.

Application filed March 25, 1921. Serial No. 455,654. Term of patent 7 years.

To all whom it may concern:

Be it known that I, ROBERT WALTER, a citizen of the United States, residing at St. Louis, county of St. Louis City, State of Missouri, have invented a new, original, and ornamental Design for Baskets, of which the following is a specification, reference being had to the accompanying drawing, forming a part thereof.

The figure is a side elevational view of a basket, showing my new design.

I claim:

The ornamental design for a basket, as shown.

ROBERT WALTER.
